(57) CLAIM

I claim a human shaped toilet stationery organizer, as shown and described.

DESCRIPTION

FIG. 1 is a front view of the human shaped toilet stationery organizer showing my new design;

FIG. 2 is a side view thereof;

FIG. 3 is a rear view thereof;

FIG. 4 is a top view thereof;

FIG. 5 is an opposite side view thereof;

FIG. 6 is a bottom view thereof;

FIG. 7 is a perspective view thereof;

FIG. 8 is an additional perspective view thereof, showing outlines of stationery items. The broken lines in FIG. 8 form no part of the claimed design; and,

FIG. 9. is an additional perspective view thereof in a disassembled state.

1 Claim, 4 Drawing Sheets
